ARM SUPPORT FOR USE ON SURGICAL
OPERATING TABLES

Alvin R. Kraus, North Hollywood, Calif.

Application March 30, 1948, Serial No. 17,915

7 Claims. (Cl. 311—10)

1

This invention relates to an arm rest or support for use on a surgical operating table.

In carrying out certain surgical operative procedures it is particularly necessary to have the arm of the patient elevated away from the operative field. Heretofore, the arm was allowed to rest on the operating table, which practice distorted the anatomical landmarks, or the arm was suspended from a stand positioned near the operating table, as by tying the wrist with a piece of gauze to the stand. This latter practice tended to impair the circulation of the blood in the arm. In either of the above described positions, the arm of the patient was so improperly supported as to cause discomfort to the patient and considerable inconvenience to the surgical staff during the course of the operative procedure.

One of the objects of my invention is the provision of means for use on a surgical operating table for comfortably supporting the arm of a patient without impairment of blood circulation in any operative procedure where the patient is required to lie on his side on said table.

A further object of my invention is the provision of a device of the foregoing character which affords a maximum of convenience to the operative staff during the course of the surgical procedure.

A still further object of my invention is the provision of a device of the foregoing character, which device is simple in construction, easily attachable to any standard type of surgical operating table and readily adjustable to conform to a variety of conditions.

Other and further objects of my invention will become apparent from the following description taken in connection with the accompanying drawing in which:

Fig. 1 is a perspective view of an arm support constructed in accordance with my invention.

Fig. 2 is a similar view on a reduced scale and showing my invention applied to a surgical operating table and in position for use.

Referring to the drawing wherein is shown a preferred embodiment of my invention, the numeral 5 designates generally a structure which comprises a tubular or rod like upright member 6, the upper end portion 7 of which is bent in an arc substantially as shown, and terminates in a bossed portion 8 which is drilled at right angles to the axis of the member 6. The arm support, generally indicated by the numeral 9 consists of a cradle shaped construction formed preferably of tubular or rod like material and includes two elongated elements 11 and 12 ar-

2

ranged in spaced relationship and connected at corresponding ends by downwardly extending substantially U-shaped elements 13 and 14, the element 13 being slightly larger than the element 14 and having suitably attached thereto an offset stub shaft 16 intended to be received for pivotal movement in the drilled bossed portion 8.

An adjustable supporting member indicated generally by the numeral 17 includes a tubular lower section 18 provided with a bifurcated terminal portion, the legs 19, 19 of which embrace the member 6 and are pivotally connected thereto. The extensible section 21 of the said supporting member includes a stem 22 telescopically receivable in the section 18 and terminating in a fork, the legs 23, 23 of which are perforated at their terminal portions to receive pins or screws 24 which are received in suitable apertures in the elements 11 and 12. An L-head set screw 26 is provided for locking the section 21 in a position of adjustment. A substantially C-shaped clamp member 27 is provided with two aligned apertures to receive the upright member 6 and is also provided with an L-head set screw 28 which serves to lock the member 6 in a position of vertical adjustment. The said clamp member is adapted to engage the marginal flanges of conventional surgical operating tables and to support the structure 5 in the manner shown in Fig. 2.

The device of my invention is intended to be used preferably with a section of tubular knitted fabric such as a stockinette 30 which is drawn over the cradle arm support 9 after removing the pins 24 from the receiving apertures. It will be understood that the component parts are reassembled before use.

The operation of the device of my invention will be apparent from the foregoing description, but briefly stated it is as follows:

While the patient is lying on his side on the operating table, the structure 5 is moved into alignment with the patient's shoulder and the height of the cradle arm support 9 is adjusted and locked in position by the set screw 28. Thereafter the elevation of the arm support 9 may be adjusted to a desired angle with relation to the axis of the member 6 by adjustment of the extensible member 17. The arm of the patient is rested comfortably on the stockinette 30 which is soft and yieldable without any binding or application of pressure of any kind to secure the arm in position.

It will thus be seen from the foregoing that with the use of my device, the arm of the pa-

tient is conveniently positioned and supported in a very comfortable manner without any impairment in the blood circulation of the patient.

I claim:

1. In an arm support including an upright member secured to an operating table, a cradle shaped arm support pivotally secured to said upright member to provide a fixed pivotal support, said arm support being long enough to support an entire arm, and means between said upright member and said arm support for adjusting the elevation of said arm support about said fixed pivotal support, said means being detachable from said arm support.

2. In an arm support including an upright member secured to an operating table, a cradle shaped frame member pivotally secured to said upright member and providing a pivotal axis for said frame member, said frame member being long enough to accommodate an entire arm, a stockinette covering said frame member, and means between said upright member and said frame member for adjusting the elevation of said frame member about said pivotal axis, said means being detachable from said frame member to permit insertion and removal of said stockinette on said frame member.

3. In an arm support for use on a surgical table including an upright member detachably secured to an operating table and means for adjusting said member with respect thereto, an arm support of a length to support thereon an entire arm, said arm support pivotally secured to said upright member and providing a pivotal axis for said arm support, adjustable means connected to said upright member and to said arm support at a point removed from said pivotal axis for changing the elevation of said arm support about said pivotal axis.

4. In an arm support including an upright member detachably secured to an operating table, an arm support of a length to support thereon an entire arm, said arm support pivotally connected at one end thereof to said upright member and providing a pivotal axis for said arm support, an adjustable member between said upright member and said arm support and connected at one end to said upright and at the other end detachably connected to said arm support at a point removed from said pivotal axis for changing the elevation of said arm support about said pivotal axis.

5. In an arm support of the class described in

cluding an upright member detachably secured to a supporting surface, a frame composed of elongated members in spaced relation and connected at corresponding ends by U-shaped members, said frame pivotally secured to said upright member and providing a pivotal axis for said frame, and an adjustable member between said upright member and said frame and connected at one end to said upright and at the opposite end detachably connected to said frame at a point removed from said pivotal axis for changing the elevation of said frame about said pivotal axis.

6. In an arm support of the class described including an upright member detachably secured to a supporting surface, a frame composed of elongated members in spaced relation and connected at corresponding ends by U-shaped members, said frame pivotally secured to said upright member and providing a pivotal axis for said frame, an adjustable member between said upright member and said frame and connected at one end to said upright and at the opposite end detachably connected to said frame at a point removed from said pivotal axis for changing the elevation of said frame about said pivotal axis, and a stockinette covering for said frame member.

7. In an arm support of the class described including an upright member detachably secured to a supporting surface, a frame composed of elongated members in spaced relation and connected at corresponding ends by U-shaped members, said frame pivotally secured to said upright member and providing a pivotal axis for said frame, an adjustable support between said upright and said frame which comprises a lower tubular section secured to said upright and a stem telescopically received in said tubular section, said stem having a pair of legs, each of which is pivotally and detachably secured to the elongated members of the frame.
